(57) **CLAIM**

The ornamental design for the sensing strip, as shown and as described.

DESCRIPTION

FIG. 1 is a perspective view of a sensing strip according to the present design;

FIG. 2 is a front view of the sensing strip according to the present design;

FIG. 3 is a rear view of the sensing strip according to the present design;

FIG. 4 is a left side view of the sensing strip according to the present design;

FIG. 5 is a right side view of the sensing strip according to the present design;

FIG. 6 is a top view of the sensing strip according to the present design; and,

FIG. 7 is a bottom view of the sensing strip according to the present design.

The broken lines depict unclaimed portions of the sensing strip and form no part of the claimed design.
